UNITED STATES PATENT OFFICE.

HENRY E. HUBBS AND LEVI D. MALONE, OF SHELBY, OHIO, ASSIGNEES TO THE SHELBY SPRING HINGE COMPANY, OF SHELBY, OHIO, A CORPORATION OF OHIO.

DOUBLE-ACTING HINGE AND CHECK.

Application filed June 30, 1926. Serial No. 119,554.

This invention is a combined double-acting hinge and check adapted for use in connection with swinging doors intended to swing in both directions, and the object of 5 the invention is to provide a simple and efficient construction of device which will permit a door connected thereto to be swung in either direction and held in its maximum open position, and at the same time will 10 check or control the movement of the door when closing so as to prevent sudden closing of the same.

Another object of the invention is to provide a device which can be quickly and accurately adjusted with reference to the door or 15 the door adjusted with reference thereto, and a still further object is to provide for the simple and easy adjustment or regulation of the device whereby the amount of checking 20 can be increased or decreased, as desired.

With these various objects in view, the invention consists in the novel features of construction and in the manner of combining or arranging the same, all of which will be 25 fully described hereinafter and set forth in the appended claims.

In the drawings forming a part of this specification, Fig. 1 is a view of a door connected with a combined double-acting hinge 30 and door check embodying my invention and this view also includes the novel construction of the upper pintle usable in connection with the door; Fig. 2 is a detail sectional view of such upper pintle and means for adjusting 35 the same; Fig. 3 is a horizontal sectional view of the combined hinge and check with the parts arranged in the positions they occupy when the door is closed; Fig. 4 is a vertical sectional view of the same; Fig. 5 is a sectional elevation on the line 5—5 of Fig. 4; Fig. 6 is a sectional view on the line 40 6—6 of Fig. 4; and Fig. 7 is a horizontal sectional view showing the position of the cam, piston and yoke when the door is being 45 swung upon its pivot.

First of all it will be understood that the combined hinge and check is concealed in the floor, and when set in cement is preferably contained within an outer metal casing 50 A sunk into an opening in the cement floor provided with lateral top flanges suitably seated in a recess or mortise in the floor, this outer casing being provided with a cover A' which is secured to the flange upon the top

of the casing and rests flush with the floor, 55 as most clearly shown.

Within the casing A, at one end thereof, is arranged the hollow casting B open at the top and also at one end and connected to this open end is the cylinder C, this cylinder being closed at the opposite end and provided with ports and a regulating valve herein-after more fully described.

The hollow casting B has a suitable bearing B' produced in the bottom thereof and in which pivots the pintle or pivot D, this pintle or pivot passing through the screw cover B² provided with the central bearing portion B³. This pivot or pintle D projects upwardly through the screw cover B² of the hollow casting and is provided at its upper end with the cross pin D' which fits into the slotted head D² of a bar D³ which is seated in a mortise cut in the bottom of the door D⁴, the opposite end of the bar having a head D⁵ into which fits the regulating screw D⁶ by means of which the bar D³ is positioned with reference to the door, and consequently the correct relation established between the door and the pintle.

The pivot or pintle D has a cam E rigid therewith, said cam working between the upper and lower members of a yoke F slotted at P' to receive the pintle D, this yoke carrying the rollers G at the rear end which contact with the rear portions of the cam and this yoke also carries a roller H with which the front portion of the cam contacts, said cam having indentations E' into which the rollers F and G fit when the door is to be held open in either direction at a position approximately 90° from its initial position. If desired only one indentation need be made so as to hold the door open on one side only.

The forward portion of the yoke F projects into the cylinder C and is pivotally connected to the rear end of a piston I working in the cylinder, the rear end of the cylinder being reduced to provide a shoulder I' against which one end of a coil spring K contacts, the opposite end of this spring contacting with the hollow casting B, as most clearly shown in Figs. 3 and 7.

The connection between the forward end of the yoke and the piston is by means of a pin F' passed vertically through the piston and yoke, the yoke end being arranged within a curved recess cut in the end of the

piston and so shaped as to permit a limited amount of lateral movement of the yoke with reference to the piston. The piston is bored centrally and longitudinally to receive a tube L screwed into the end of the cylinder.

The cylinder is formed with a vertical chamber C' having a reduced lower end C³ and a tapered seat C² between the chamber 10 C' and reduced portion C³ and leading from this reduced portion C³ is a passage C⁴ communicating with the cylinder forward of the piston. A passage C⁵ communicates with the tube L and thereby establishes communication between the chamber C' and the rear side of the piston.

Located in the chamber C' is a valve pin M having a tapered end M² at its lower end adapted to cooperate with the seat C² to 20 regulate the passage of fluid therethrough, the upper end of the pin being threaded as shown at M' and working through a collar or plug M³ screwed into the upper end of the chamber C', there being interposed a packing M⁴ to prevent leakage.

There is an opening A² in the cover plate A' to permit the adjustment of the regulating pin or valve, said pin or valve being provided at its upper end with a slot 30 for the reception of a screw driver or other tool for the purpose of adjustment.

The piston also has a longitudinal passage N reduced at its rear end and providing a valve seat N' against which the ball valve N² seats during the forward movement of the piston, this ball valve being held in place by means of a pin N³ extending across the forward end of the passage N.

40 It will thus be seen that there is provided a double check, one carried by the piston and the other by the cylinder, the latter being adjustable to regulate the passage of fluid therethrough. In practice it 45 is preferred to employ oil as the fluid controlling medium but it will, of course, be understood that any suitable fluid can be employed, and in this connection air will be considered a fluid for such purposes in 50 case it should be desired to dispense with a liquid controlling medium.

A leather washer X is placed between the screw cover B² and the casting and I also employ a leather washer Y and disk Z 55 rounding the pintle where it passes out of the screw cover, these washers being employed to prevent the escape of oil or other checking liquid.

As the door is swung in either direction, the yoke will be forced rearwardly drawing with it the piston. During these movements fluid will pass through the piston head both through the check valve and the central tube L, but upon the return 65 movement, the check valve will seat to pre-

vent the passage of fluid at that point thereby forcing the liquid through the passage C⁴ past the regulating needle valve C² and out through the opening C⁵ and, as previously stated, by regulating the needle valve, any degree of retardation can be had. The spring is of course employed to bring about the return movement of the door, this spring being placed under compression when the door is moved in either direction.

In operation the outer casing is first positioned in the floor and the hollow casting with cylinder connected thereto is arranged within the outer casing and the cover plate A' is then securely fastened in place flush with the floor. The door to which the bar D³ has been attached is then positioned upon the pintle D and cross pin D' and the door is properly centered by means of the adjusting screws D⁵ in order to maintain the lower end of the door in the proper relative position with reference to the combined hinge and check.

At the upper end of the door there is placed a pintle socket O into which fits the upper pintle P, this pintle being arranged in the socket Q arranged at the top of the door frame, this socket being slotted as shown at Q' to permit the movement of the adjusting finger R fitting into the upper end of the pintle P and provided with a threaded opening at its other end in which works a screw S the head of which is countersunk in the plate portion of the upper socket. This screw is held against vertical movement by means of a washer S', said washer being set in a groove S² cut in the shank next to the head. The washer is flattened out after insertion in the groove. The washer contacts with the pintle casting and holds the screw against vertical movement but permits rotation.

In operation the socket Q is inserted in the door frame and the pintle P is drawn upwardly by turning the screw S, moving the finger R upwardly, withdrawing the pintle into the socket. The socket portion O having been previously positioned in the top of the door D⁴, is moved beneath the pintle P, and while the door is turned to a position at right angles, the screw S is turned in the reverse direction, bringing the pintle P downwardly into the socket O.

It will thus be seen that we provide a simple construction of adjustable pintle for the upper end of the door as well as a simple and efficient hinge and check for the lower end of the door.

Having thus described our invention, what we claim is:

1. In a combined hinge and check, the combination with a hollow casting and cylinder connected thereto, of a pintle journaled in the casting and having a cam connected thereto, a yoke provided with rollers ar-

- ranged for engagement with the cam and whereby the yoke is moved as the pintle turns, a piston movable in the cylinder and pivotally connected to the forward end of the yoke, a coil spring arranged in the cylinder and engaging the piston, a check valve arranged in a passage in the piston, a chamber at the forward end of the cylinder, an adjustable valve arranged in said chamber, 5 said chamber having two outlets, and a tube communicating with one of said outlets and arranged centrally of the piston.
2. In a combined hinge and check, the combination with a hollow casting and a cylinder connected thereto, of a pintle journaled in the hollow casting and having a cam rigidly connected thereto, a longitudinally slotted yoke having rollers arranged for engagement with the cam and whereby 10 the yoke is moved longitudinally as the pintle rotates, a piston pivotally connected to the forward end of the yoke and reciprocating in the cylinder, said piston having a central bore and likewise a passage adjacent one 15 side, a check valve located in said passage, a chamber in the end of the cylinder the lower end of said chamber being reduced and provided with a valve seat adjacent said reduced end, an opening communicating 20 with the reduced end of the chamber and the body of the cylinder, an adjustable valve arranged in said chamber and seating upon said seat, a central opening communicating with said chamber and a tube communicating with said central opening and arranged 25 centrally of the piston and upon which the piston moves as set forth. 35
3. In a combined check and hinge, the combination with a hollow casting, cylinder, pintle, yoke and piston, a spring for moving 40 said piston forwardly, the forward end of the cylinder having a vertically disposed chamber the lower end of which is reduced and provided with a valve seat, there being an opening communicating with the reduced 45 end of said chamber and the body of the cylinder, a second opening communicating with said chamber about midway its height, a tube secured in the end of the cylinder and communicating with said opening, the piston being movable upon said tube, an adjustable valve arranged in the chamber and adapted to seat upon the valve seat at the lower end thereof together with means for maintaining said valve sealed in its adjusted 50 position. 55

In testimony whereof, we hereunto affix our signatures.

HENRY E. HUBBS.
LEVI D. MALONE.
